US0D1069878S

(12) **United States Design Patent** (10) **Patent No.:** **US D1,069,878 S**
(45) **Date of Patent:** **** Apr. 8, 2025**

(54) **PROJECTOR LENS**

(71) Applicant: **Shenzhen Chuangxin Intelligent Lighting Technology Co., Ltd., Shenzhen (CN)**

(72) Inventor: **Liting Luo, Zhanjiang (CN)**

(73) Assignee: **Shenzhen Chuangxin Intelligent Lighting Technology Co., Ltd., Shenzhen (CN)**

(**) Term: **15 Years**

(21) Appl. No.: **29/979,655**

(22) Filed: **Dec. 19, 2024**

(51) **LOC (15) Cl.** **26-05**

(52) **U.S. Cl.**

USPC **D26/124**

(58) **Field of Classification Search**

USPC D16/130, 134, 136, 137, 100, 101;
D26/120, 124
CPC G02B 27/283; G02B 1/043; G02B 5/045;
G02B 3/00

(57) **CLAIM**

The ornamental design for a projector lens, as shown and described.

DESCRIPTION

FIG. 1 is a top, front, right side perspective view of a projector lens, showing my new design;
FIG. 2 is a bottom, rear, left side perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof; and,
FIG. 8 is a bottom plan view thereof.

1 Claim, 8 Drawing Sheets
